UNITED STATES PATENT OFFICE.

CLARENCE T. MAPES, OF CRAFTON, AND FERDINAND C. YANDA, OF PITTSBURGH, PENNSYLVANIA, ASSIGNORS TO OIL WELL SUPPLY COMPANY, OF PITTSBURGH, PENNSYLVANIA, A CORPORATION OF PENNSYLVANIA.

CLAMP FOR WELL-DRILLING CABLES.

1,169,849.

Specification of Letters Patent.

Patented Feb. 1, 1916.

Application filed January 6, 1915. Serial No. 767.

To all whom it may concern:

Be it known that we, CLARENCE T. MAPES and FERDINAND C. YANDA, citizens of the United States, and residents of Crafton and Pittsburgh, respectively, in the county of Allegheny and State of Pennsylvania, have invented certain new and useful Improvements in Clamps for Well-Drilling Cables, of which the following is a specification.

10 This invention relates to that type of clamps for well drilling cables wherein the hold on the cable is obtained by the eccentric action of opposed jaws as distinguished from a wedging action such as results from the use of tapered or wedge-shaped slips, and the primary object is to provide a pair of opposed jaws of improved construction, together with improved means for holding and retaining the jaws in the body.

20 A further purpose is to provide a clamp of the general type stated, wherein the clamp-suspending means is connected directly to the body instead of to the lighter and more easily broken jaws as heretofore proposed.

25 In the accompanying drawings, Figure 1 is a front elevation of the improved clamp, and Fig. 2 is a view in top plan of the same. Figs. 3 and 4 are vertical sections, taken on lines 3—3 and 4—4, respectively, of Fig. 2. Fig. 5 is a sectional plan, taken on line 5—5 of Fig. 4.

Referring to the drawings, 2 designates the clamp body which is formed with the vertical cylindrical bore 3, the latter being open at one side through a vertical face to form the cable slot or passage 4. Projecting from the upper portion of the body at diametrically opposite sides of the bore are the hook-like ears 5 for receiving the usual reins, not shown, for suspending the clamp from the temper screw swivel bar of well drilling apparatus in manner familiar in the art. The body bore and the supporting ears 40 are located at one side of the center of the body so that the latter may be properly balanced when suspended, the heavier rear side of the body balancing the weight of the jaw arms and arm-adjusting means projecting 45 from the front thereof, as will presently be described. The link-like supporting reins are preferably confined in ears 5 by pins or bolts 6, the latter being entered from beneath and with their headed extremities

disposed downwardly and thus presenting 55 no obstructing projection which would be liable to injury if exposed at the upper sides of the ears.

Operative within bore 3 is the pair of opposed jaws 7. Each jaw is formed with an 60 elongated body portion 8 of segmental shape in cross-section and with its outer face curved to fit and rotate within the cylindrical bore 3. The jaws are preferably of such length that they depend beneath the lower 65 end of body 2, while at their upper ends they are flanged laterally at 7' to engage the flat top bearing face 9 of body 2, said face encircling bore 3 and interrupted only by the cable passage 4. By this means the jaws 70 are rotatably supported in the body bore, with flanges 7' holding them against downward displacement. An arm 10 projects laterally from each jaw, and these arms are 75 operative in the lateral enlargements 11 in opposite walls of cable passage 4, these enlargements being located intermediate the upper and lower ends of the clamp body and affording the jaws and their arms free movement as required for clamping and for 80 releasing the cable. With the jaw bodies 8 of segment shape in cross-section they may be rotated into the full open position shown in Fig. 5, with the rear faces of the jaws in engagement with each other and with arms 10 85 moved fully backward or outward into the passage enlargements 11. Arms 10 and cable passage 4 are of such size that when positioning the jaws by moving them downward one after the other into bore 3, the arm 90 is passed downwardly through passage 4 until it reaches enlargement 11.

For clamping the drilling cable C, the faces of the jaws are formed with semi-circular depressions 12 located at one side of or 95 eccentric to the center of bore 3, and fitting these depressions are the cable-gripping liners or slips 13. The liners are flanged at their upper ends at 13' to fit corresponding enlargements of the upper extremities of 100 cavities 12, and by this means together with the countersunk securing screws 14 entered through the jaws, the liners are securely held. Liners of various sizes may be provided for adapting the same clamp to cables 105 of different diameters, and with the gripping elements thus arranged, the parts most exposed to wear, *i. e.*, the liners, may be re-

newed at comparatively small expense. For adjusting the jaws, a yoke 15 is secured by hinge bolt 16 to one of the arms 10, the yoke being adapted to swing into embracing engagement with both arms, as in Figs. 1 and 2, and carrying the screw 17 for obtaining the desired adjustment.

It is characteristic of the invention that the clamp-suspending means are connected 10 to the clamp body rather than to the jaws, thereby relieving the latter of destructive strains. At the same time the jaws are positively supported by the body, the flanged upper extremities of the jaws bearing on surface 9 in whatever position the jaws may be turned, the interruption of said bearing surface formed by cable passage 4 being bridged in part by both jaws as when the parts are in the symmetrical adjustment shown in Figs. 15 1 and 2, or by the flange of one jaw more than the other if turned to one side. In any case, the support is secure and positive and at right angles to the elongated gripping hold of the jaws, such hold being of 20 uniform pressure from end to end of the pair of jaws.

We claim:

1. In cable-suspending means and in combination, a clamp body having a vertical bore of fixed dimensions and a cable-entering passageway leading into said bore, opposed cable-gripping jaws extending through and rotatable within the bore, each jaw being flanged outwardly at its upper end, said flanges being adapted to rest upon the top of the clamp body to support the jaws, and jaw-adjusting means, said latter means including an element carried by and movable with each jaw, said elements coöperating in 30 moving the jaws to cable-gripping position and maintaining them in such position, said body being recessed to permit free movement of said elements.
2. In cable suspending means and in com-

bination, a clamp body having a vertical 45 bore of fixed dimensions and a cable-entering passageway leading into said bore, opposed cable-gripping jaws extending through and rotatable within the bore, each jaw being flanged outwardly at its upper end, said 50 flanges being adapted to rest upon the top of the clamp body to support the jaws, and jaw-adjusting means, said latter means including an element carried by and movable with each jaw, said elements coöperating in 55 moving the jaws to cable-gripping position and maintaining them in such position, said body being recessed to permit free movement of said elements, said cable-entering passageway having a width to permit the 60 passage of either of said elements when alined therewith, but insufficient to permit simultaneous passage of both elements.

3. In cable suspending means and in combination, a clamp body having a vertical 65 bore of fixed dimensions and a cable-entering passageway leading into said bore, opposed cable-gripping jaws extending through and rotatable within the bore, each jaw being flanged outwardly at its upper end, said 70 flanges being adapted to rest upon the top of the clamp body to support the jaws, and jaw-adjusting means, said latter means including an element carried by and movable with each jaw, said elements coöperating in 75 moving the jaws to cable-gripping position and maintaining them in such position, said body being recessed to permit free movement of said elements, said body carrying members independent of the jaws to permit 80 suspension of the body.

In testimony whereof we affix our signatures in presence of two witnesses.

CLARENCE T. MAPES.
FERDINAND C. YANDA.
